UNITED STATES PATENT OFFICE.

WILLIAM S. HOVEY, OF THREE RIVERS, MICHIGAN, ASSIGNOR TO THE SHEFFIELD CAR COMPANY, OF THREE RIVERS, MICHIGAN.

LOCOMOTIVE.

No. 870,560.

Specification of Letters Patent.

Patented Nov. 12, 1907.

Application filed October 18, 1906. Serial No. 339,534.

To all whom it may concern:

Be it known that I, WILLIAM S. HOVEY, a citizen of the United States, residing at Three Rivers, county of St. Joseph, and State of Michigan, have invented certain new and useful Improvements in Locomotives, of which the following is a specification.

This invention relates to improvements in locomotives.

The objects of this invention are, first, to provide an improved locomotive which derives its power from an explosion engine, which is simple in construction and easy to operate. Second, to provide an improved locomotive which may be readily driven in either direction.

Further objects, and objects relating to structural details, will definitely appear from the detailed description to follow.

I accomplish the objects of my invention by the devices and means described in the following specification.

20 The invention is clearly defined and pointed out in the claims.

A structure embodying the features of my invention is clearly illustrated in the accompanying drawings, forming a part of this specification, in which,

25 Figure 1 is a detail side elevation of a structure embodying the features of my invention, portions being broken away and other portions being shown in conventional form, for convenience in illustration. Fig. 2 is a front elevation of the structure appearing in Fig. 1, the 30 water coil and the supporting parts therefor being removed. Fig. 3 is an enlarged detail longitudinal section through the transmission gear. Fig. 4 is a vertical section through the transmission gear, showing the arrangement of the driven shaft 32, and the reversing 35 mechanism therefor.

In the drawing, similar reference characters refer to similar parts throughout the several views.

Referring to the drawing, the frame 1 of my improved locomotive is preferably built up of channel iron to secure 40 strength and rigidity. The frame is supported by the carrying and driving wheels 3, shown in conventional form, the connection for the frame to the axles 2 not being illustrated.

The engine may be of any desired type and size, that 45 shown in the drawing being a double cylinder explosion engine. The engine is arranged longitudinally, the crank shaft thereof being supported in suitable bearings. The crank shaft is preferably connected to the transmission shaft 5 by a universal joint 6 (see Figs. 50 1 and 3), the bearings 7 for the transmission shaft being arranged on the casing 8 for the transmission gear. The details of the joint or coupling 6 are not here illustrated or described, as it may be of any suitable form of the so-called universal joint. By thus joining the crank shaft 55 to the transmission shaft, the parts are not injured by

the springing of the frame or by the parts getting out of alignment and the vibration of the engine does not seriously affect the same.

The fly wheel 9 is fixed to the crank shaft, as clearly appears in Fig. 1. On the transmission shaft 5 are gears 10, 11 and 12. The gears 10 and 11 are secured or fixed to the shaft, and the gear 12 is revolvably mounted thereon. The gear 12 is secured to the shaft by means of a clutch mechanism consisting of the sliding grooved collar 13, which is adapted to engage the pivoted lever-like dog 14 to force it into engagement with the plate 15 slidably secured to the shaft. The friction disk 16 is provided with arms 17, which are arranged through the gear 11 to be engaged by the plate 15. The dog 14 is carried by the collar 17, which is secured to the shaft. Arranged above the transmission shaft 5 and transversely thereof is a rock shaft 18, having a forked arm 19 thereon arranged to engage the grooved clutch collar for shifting the same.

Arranged parallel with the transmission shaft 5 is a 75 shaft 20 mounted in suitable bearings 24 in the casing 8. On this shaft 20 are gears 21, 22 and 23, the gears 21 and 22 being revolvably mounted upon the shaft and the gear 23 being fixed thereto.

The gear 21 is arranged to mesh with the gear 10 on 80 the shaft 5; the gear 22 is arranged to mesh with the gear 11; and the gear 23 is arranged to mesh with the gear 12. The gears 21 and 22 are secured or clutched to the shaft by means of a mechanism preferably consisting of the friction disks 25, which are locked against 85 the gear by the dogs 26, these dogs being pivoted on the collars 27 fixed to the shaft. The grooved clutch collar 28 is provided with conical surfaces, which, when forced under these dogs, clamp them against the friction disks or plates. 90

The clutch collar 28 is shifted by means of the rock shaft 29, which is provided with a bifurcated arm 30 arranged to engage the collar. On the shaft 20 is a beveled gear 31. Arranged transversely of the shaft 20 is a driven shaft 32, having beveled gears 34 thereon 95 arranged to mesh with the gear 31 on the shaft 20. Either of these gears 34 may be secured to the shaft by means of the jawed clutch 35 which is slidably mounted on the shaft. This clutch is operated by the bifurcated arm 36 carried by the rock shaft 37; 100 see Fig. 3.

The shaft 32 is provided with a pair of sprocket wheels 38; see Fig. 4. These sprocket wheels are connected to the front and rear axles by sprocket chains 39, the axles being provided with sprocket 105 wheels 40, indicated in conventional form in the drawing.

On the shaft 32 is a brake wheel or drum 41 having a brake band 42 thereon. The brake band is operated by the lever 43. As the details of this may be ar- 110

ranged as desired, I do not illustrate or describe the same herein. By means of the gears described, the lower transmission shaft 20 may be driven by any one of the trains of gears described, thereby securing three 5 different speeds, and by means of reversing the mechanism, these speeds may be secured in either direction. It is evident that more speeds could be secured by adding or increasing the number of gears and clutches on the transmission shafts 5 and 20.

- 10 The various clutches are controlled or adjusted by means of the hand levers 44, 45 and 46. The hand lever 44 is connected by the rod or link 47 to the arm 48 on the rock shaft 18. This connects the high-speed gear 12, when thrown forward and releases this clutch 15 and applies the brake band 42 when thrown rearwardly, the lever being connected to the brake lever 43 of the brake band by means of the link 49. When in its neutral position, as illustrated, neither the clutch nor the brake band is in operation. The lever 20 45 is connected to the rock shaft 29 of the clutch mechanism for the gears 21 and 22 by means of the link or rod 50, which is connected to one arm of the bell crank lever 51, this lever being mounted on the rock shaft 18. The other arm of the bell crank 51 is connected by the link 52 and the arm 53 on the rock shaft 29; see Figs. 1 and 2, the parts appearing by dotted lines in Fig. 1. By shifting this lever so that the gear 21 is locked to the shaft, a slow speed is secured; by shifting it so that the gear 22 is locked to 25 the shaft, an intermediate speed is secured; when in a neutral position, neither clutch is engaged. The lever 46 controls the shifting of the jaw clutch 35 on the shaft 32 for locking either of the gears 34 thereto and thus securing the driving in the desired direction. 30 The lever is connected by means of the link 54 and an arm 55 on the rock shaft 37 of the clutch jaw. The lever is provided with a suitable latch adapted to engage the toothed segment 56 so that it may be locked either forward or rearward for locking the clutch 40 in engagement with one or the other of the gears 34 and with a central notch for locking it in its neutral position, in which case both of the gears 34 are loose and the engine runs free.

In the structure illustrated, I show a water coil 45 supported on a suitable bracket 61 on the forward end of the main frame. This water coil is arranged in a casing 62 which is provided with a stack or flue 63. The exhaust pipe 64 from the engine is arranged through this casing, and is provided with an upwardly directed discharge nozzle 65 arranged to discharge into the base or bottom of the flue thereby securing an injector effect to create a current of air through the water coil casing. By this arrangement, the exhaust is effectively utilized for cooling the water coil.

I have especially designed my improved locomotive for use on railways, where an easy operating and convenient locomotive is desired, the same being of especial advantage in construction work for running over 60 temporary tracks and the like, on which it would not be safe to operate a heavy locomotive. It is, however, adapted, as is evident, to a great variety of uses.

By arranging the engine longitudinally, the structure may be adjusted to any desired gage without 65 disturbing any of the driving mechanism, merely by

changing the axles. By the means described, both axles are driven and a maximum traction power is secured. By joining the transmission shaft and the crank shaft to the engine by a universal joint, undue strain of the parts, through vibration of the engine or 70 the springing or getting out of alinement of the frame, as is likely to occur, produces no serious results.

By means of the transmission described, the locomotive may be driven in either direction with equal facility at three speeds. However, as previously 75 stated, this transmission could be modified, or other transmissions used in combination with the other features with satisfactory results. The system of levers and connections described for controlling the engine are simple, and, at the same time, the locomotive is under perfect control.

I have illustrated and described my improved locomotive in detail in the form preferred by me on account of the structural simplicity and economy and convenience in operating. I am, however, aware 85 that it is capable of considerable variation in structural details without departing from my invention.

Having thus described my invention, what I claim as new and desire to secure by Letters Patent is:

1. The combination with a suitable frame, of a pair 90 of axles; traction wheels on said axles; an engine arranged longitudinally of said frame; a transmission gear comprising a transmission shaft connected to the engine crank shaft by a universal joint; a second transmission shaft, said transmission shafts being arranged 95 longitudinally of said frame; a plurality of gears arranged in trains to connect said transmission shaft whereby the speed of said second transmission shaft may be varied; a driven shaft arranged transversely of said transmission shafts; a beveled gear on the second of 100 said transmission shafts; a pair of beveled gears revolvably mounted on said driven shaft arranged to mesh with said gear on said transmission shaft; a clutch mechanism by which either of said gears may be connected to said driven shaft; a pair of sprocket wheels 105 for said driven shaft; sprockets on said axles; sprocket chains connecting the same to said driven shaft; and a brake mechanism for said driven shaft, for the purpose specified.

2. The combination with a suitable frame, of a pair of axles; traction wheels on said axles; an engine arranged longitudinally of said frame; a transmission gear comprising a transmission shaft connected to the engine crank shaft by a universal joint; a second transmission shaft, said transmission shafts being arranged longitudinally of said frame; a plurality of gears arranged 115 in trains to connect said transmission shafts whereby the speed of said second transmission shaft may be varied; a driven shaft arranged transversely of said transmission shafts; a beveled gear on the second of 120 said transmission shaft; a pair of beveled gears revolvably mounted on said driven shaft, arranged to mesh with said gear on said transmission shaft; a clutch mechanism by which either of said gears may be connected to said driven shaft; a pair of sprocket wheels for said 125 driven shaft; sprockets on said axles; and sprocket chains connecting the same to said driven shaft, for the purpose specified.

3. The combination with a suitable frame, of a pair of axles; traction wheels on said axles; an engine arranged longitudinally of said frame; a transmission gear comprising a transmission shaft connected to the engine crank shaft by a universal joint; a second transmission shaft, said transmission shafts being arranged longitudinally of said frame; a plurality of gears arranged 130 in trains to connect said transmission shafts whereby the speed of said second transmission shaft may be varied; a driven shaft arranged transversely of said transmission shaft; a beveled gear on the second of

said transmission shafts; a pair of beveled gears revolu-
bly mounted on said driven shaft arranged to mesh with
said gear on said transmission shaft; a clutch mechanism
by which either of said gears may be connected to said
5 driven shaft; driving connections for said driven shaft
to said axles; and a brake mechanism for said driven
shaft, for the purpose specified.

shaft, for the purpose specified.

4. The combination with a suitable frame, of a pair of axles; traction wheels on said axles; an engine arranged longitudinally of said frame; a transmission gear comprising a transmission shaft connected to the engine crank shaft by a universal joint; a second transmission shaft, said transmission shafts being arranged longitudinally of said frame; a plurality of gears arranged in 10 trains to connect said transmission shafts whereby the speed of said second transmission shaft may be varied; a driven shaft arranged transversely of said transmission shafts; a beveled gear on the second of said transmission shafts; a pair of beveled gears revolvably mounted on 15 said driven shaft arranged to mesh with said gear on said transmission shaft; and a clutch mechanism by which either of said gears may be connected to said driven shaft; and driving connections for said driven shaft to said axles for the purpose specified.

20

25 shaft to said axles, for the purpose specified.
5. The combination with a suitable frame, of a pair
of axles; traction wheels on said axles; an engine ar-
ranged longitudinally of said frame; a transmission gear
comprising a transmission shaft, connected to the engine
crank shaft; a second transmission shaft, said trans-
mission shafts being arranged longitudinally of said frame;
30 a plurality of gears arranged in trains to connect said
transmission shafts whereby the speed of said second
transmission shaft may be varied; a driven shaft ar-
ranged transversely of said transmission shafts; a
beveled gear on the second of said transmission shafts;
35 a pair of beveled gears revolvably mounted on said driven
shaft arranged to mesh with said gear on said trans-
mission shaft; a clutch mechanism by which either of
said gears may be connected to said driven shaft; a pair
40 of sprocket wheels for said driven shaft; sprockets on
said axles; sprocket chains connecting the same to said
driven shaft; and a brake mechanism for said driven
shaft, for the purpose specified.

45 6. The combination with a suitable frame, of a pair of axles; traction wheels on said axles; an engine arranged longitudinally of said frame; a transmission gear comprising a transmission shaft, connected to the engine crank shaft; a second transmission shaft, said transmission shafts being arranged longitudinally of said frame; a plurality of gears arranged in trains to connect said transmission shafts whereby the speed of said second transmission shaft may be varied; a driven shaft arranged transversely of said transmission shafts; a beveled gear on the second of said transmission shafts; a pair of beveled gears revolvably mounted on said driven shaft arranged to mesh with said gear on said transmission shaft; a clutch mechanism by which either of said gears may be connected to said driven shaft; a pair of sprocket wheels for said driven shaft; sprockets on said axles; and sprocket 50 chains connecting the same to said driven shaft, for the purpose specified.

purpose specified.

7. The combination with a suitable frame, of a pair of axles; traction wheels on said axles; an engine arranged longitudinally of said frame; a transmission gear comprising a transmission shaft connected to the engine crank shaft; a second transmission shaft, said transmission shafts being arranged longitudinally of said frame; a plurality of gears arranged in trains to connect said transmission shafts whereby the speed of said second transmission shaft may be varied; a driven shaft arranged transversely of said transmission shafts; a beveled gear on the second of said transmission shafts; a pair of beveled gears revolubly mounted on said driven shaft arranged to mesh with said gear on said transmission shaft; a clutch mechanism by which either of said gears may be connected to said driven shaft; driving connections for said driven shaft to said axles, for the purpose specified.

8. The combination with a suitable frame, of a pair of axles; traction wheels on said axles; an engine arranged longitudinally of said frame; a variable speed transmission gear therefor; a driven shaft arranged transversely of said frame; a beveled gear connected to said transmission gear; a pair of beveled gears revolubly mounted on said driven shaft arranged to mesh therewith; a clutch by which either of said gears may be connected to said driven shaft; a pair of sprocket wheels for said driven shaft; sprockets on said axles; and sprocket chains connecting the same to said driven shaft, for the purpose specified.

9. The combination with a suitable frame, of a pair of axes; traction wheels on said axes; an engine arranged longitudinally of said frame; a variable speed transmission gear therefor; a driven shaft; a beveled gear connected to said transmission gear; a pair of beveled gears revolubly mounted on said driven shaft arranged to mesh therewith; a clutch by which either of said gears may be connected to said driven shaft; and driving connections for said driven shaft to said axes, for the purpose specified. 90
95

10. The combination with a suitable frame, of a pair of axes; traction wheels on said axes; an engine; a variable speed transmission gear therefor; a driven shaft arranged transversely of said frame; a beveled gear connected to said transmission gear; and a pair of beveled gears revolvably mounted on said driven shaft arranged to mesh therewith; a clutch by which either of said gears may be connected to said driven shaft; a pair of sprocket wheels for said driven shaft; sprockets on said axes; and sprocket chains connecting the same to said driven shaft, for the purpose specified.

purpose specified. 110
11. The combination with a suitable frame, of a pair of axes; traction wheels on said axes; an engine; a variable speed transmission gear therefor; a driven shaft; a bevelled gear connected to said transmission gear; a pair of bevelled gears revolubly mounted on said driven shaft arranged to mesh therewith; a clutch by which either of said gears may be connected to said driven shaft; and driving means for said driven shaft to said axes, for the purpose - 115
specified.

13. The combination with a suitable frame, of a pair of axles; traction wheels on said axles; an engine arranged longitudinally in said frame; a driven shaft; a pair of beveled gears revolvably mounted on said driven shaft; a clutch by which either of said gears may be connected to said driven shaft; a beveled gear driven by said engine arranged to mesh with said gears on said driven shaft; and driving connections for said driven shaft to said axles, for the purpose specified. 130
135

14. The combination with a suitable frame, of a pair of axles; traction wheels on said axles; an engine; a driven shaft arranged transversely of said frame; a pair of bevelled gears revolubly mounted on said driven shaft, a clutch by which either of said gears may be connected to said driven shaft; a bevelled gear driven by said engine arranged to mesh with said gears on said driven shaft; a pair of sprocket wheels for said driven shaft; sprockets 145 on said axles; and sprocket chains connecting the same to said driven shaft, for the purpose specified.

In witness whereof, I have hereunto set my hand and seal in the presence of two witnesses.
